UNITED STATES PATENT OFFICE.

JOHN POLACHEK, OF NEW YORK, JULIUS JEPSEN, OF BROOKLYN, AND EDMUND PEREMI, OF NEW YORK, N. Y., ASSIGNORS TO JOHN POLACHEK, OF LONG ISLAND, NEW YORK, DOING BUSINESS AS JOHN POLACHEK BRONZE & IRON CO.

WINDOW.

Application filed May 2, 1923. Serial No. 636,156.

To all whom it may concern:

Be it known that we, JOHN POLACHEK, JULIUS JEPSEN, and EDMUND PEREMI, citizens of the United States, and residents, 5 respectively, of the city of New York, borough of Manhattan, in the county and State of New York, of the city of New York, borough of Brooklyn, in the county of Kings and State of New York, and of the 10 city of New York, Elmhurst Manor, Long Island, borough of Queens, in the county of Queens and State of New York, have invented a new and Improved Window, of which the following is a full, clear, and 15 exact description.

This invention relates to improvements in windows and has particular reference to a metallic window construction.

An object of the invention is to provide 20 an improved window wherein the window frame and sashes are so constructed and interengaged that the same will effectively prevent the ingress of air and dust into a room when the sashes are in closing position.

Another object is the provision of an improved window in which the frame and sashes are so assembled that any rattling of the sashes, due to lateral movement thereof 30 with respect to the frame, will be prevented.

A further object is to so construct the frames and sashes that the window may be readily and quickly assembled in operative position.

The above and other objects will appear 35 more clearly from the following detail description, when taken in connection with the accompanying drawings, which illustrate a preferred embodiment of the inventive idea.

In the drawings—

Figure 1 is a front elevation of the window constructed in accordance with the invention;

Figure 2 is a fragmentary transverse section of the window showing both sashes in cross section;

Figure 3 is a vertical sectional view of the window with both sashes in closing position; and

Figure 4 is a perspective view of one of the stiles of the sashes.

The window is made of any desired ma-

terial, such as steel or bronze, which is rolled or extruded to form the various parts of the window. The frame of the window comprises the side, top and sill sections 5, 6 and 7, respectively. Inasmuch as the side and top sections are identical in construction, a description of one will suffice for 55 both and similar characters will be used to designate like parts. The side sections, only one of which is illustrated in Figure 2, each comprises the outer, intermediate and inner portions 8, 9 and 10, respectively, the intermediate portion being secured along its longitudinal edges with the adjacent overlapping longitudinal edges of the outer and inner sections by means of suitable fasteners 11. Forming a part of the inner portion 10 is a stile 12 secured to said portion by means of fasteners 13. Medially of its longitudinal edges the intermediate portion 9 is bent to provide a parting strip 14 and on opposite sides of said parting strip the 70 portion 9 is further provided with flanges 15 which combine with the sides of the parting strip to form grooves 16 for a purpose 75 which will presently appear. The sides of the parting strip 14 are also formed with 80 vertically disposed grooves 17 similar to grooves 18 formed in opposed surfaces of the portion 8 and the stile 12.

The sill section 7 is of channeled formation so as to receive a suitable material 19 85 utilized to securely anchor said section in proper position with respect to the sill of the window opening. Intermediate the edges of the section 7 the same is provided with an upwardly projecting portion 20 90 having the sides 21 and 22, the former of which cooperates with a flange 23 to form a groove 24 for a purpose which will appear in the course of the description.

The window further comprises the upper and lower sashes 25 and 26 which are practically identical in construction. The sashes 25 and 26 include stiles, generally indicated by the numeral 27, the upper and lower rails 28 and 29 and the meeting rails 100 30 and 31. The stiles 27 and the upper and lower rails 28 and 29 are substantially alike in construction and each includes a web portion 32 having the flanges 33 extending from the longitudinal edges thereof in the 105 same direction and in parallel relation.

Formed integrally with one of the flanges 33 and extending from the inner face thereof and intermediate its longitudinal edges is a diagonally disposed flange 34 which 5 combines with the outer portion of said flange 33 to form a substantially V-shaped groove 35. The grooves 35 of the various stiles 27 and upper rail 28 are designed to receive the flanges 15 of the intermediate 10 portions of the side and top sections of the frame, the outer portions of the flanges 33 upon which the flanges 34 are formed then engaging in the grooves 16, thus forming a connection between the sashes and frame, 15 which will prevent lateral movement and consequent rattling of the sashes. The outer surfaces of the last named flanges 33 of the stiles 27 and upper rail 28 engage the sides of the parting strip 14 and combine 20 with the grooves 17 therein to form small air chambers which aid in preventing air passing around the sashes into the interior of a room. This passage of the air is further prevented by the plurality of points of 25 contact between the flanges 15, 33 and 34. In addition to the air chambers formed by the grooves 18 the outer flanges 33 of the stiles 27 and upper rail 28 combine with the grooves 18 in the members 8 and 12 to 30 form other air chambers. Also the stiles 27 and upper rail 28 combine with the sections 5 and 6 of the frame to form the large air chambers 36. Adjacent one of the longitudinal edges of the web portion 32 of 35 each stile and upper rail another flange 37 extends in the opposite direction from the flanges 33 but in parallel relation thereto and this flange 37 is utilized in securing the pane of glass in the window 40 sash, as clearly illustrated in Figures 2 and 3.

The flanges 38 and 39 of the lower rail 29 of the lower sash are of different widths and the flange 38 is provided with a flange 45 40 similar to the flanges 34 to form a groove for receiving the flange 23 when the lower sash is in closing position. The flange 40 then also engages in the groove 24 to form a joint between the lower rail and sill similar to that described in connection with the 50 stiles 27 and upper rail 28. The inner flange 39 of the lower rail overlaps the side 22 of the portion and said lower rail combines with the sill section to form the air 55 chamber 41 similar to the chambers 36. The meeting rails 30 and 31 are provided, respectively, along their adjacent edges with flanges 42 and 43 which overlap and interengage, as illustrated in Figure 3, when 60 the sashes are in closing position. Disposed on each side of the window and extending partially over the top thereof are the casings 44, in which the parting strips 45 are disposed for dividing the casings into 65 compartments for receiving the usual counterweights 47 for the sashes. The intermediate portions 9 of the side sections of the frame may be provided, if desired, with rubber bumpers 48 supported by means of plates 49 and against which the lower sash 70 may engage to prevent noise when opening the window. The intermediate portions 9 may be displaced, by removing the screws 11, whereby access may be had to the interior of the casings 44 to repair or replace parts therein. The lower sash 26 may be provided with an operating handle 50 to facilitate the raising and lowering of the sash. The meeting rails 30 and 31 are locked together by a locking device 51 of 80 any desired construction. The outer portions 8 of the side sections may have anchored therein the rings 52 utilized for the purpose of attaching a safety belt thereto when washing the window. 85

What is claimed is:

1. In a window construction, a window frame having a section thereof including an intermediate portion formed with a parting strip, and a window sash engageable with said parting strip, said portion and sash having cooperating flanges for presenting an air chamber, one of said flanges on said frame combining with said parting strip to form a groove for receiving a flange 90 extending from said sash and one of said flanges on one member contacting with a side of said parting strip and being interposed between the latter and a flange on the other member. 95
2. In a window construction, a window frame having side and top sections each including outer, intermediate and inner members, said intermediate members being formed with a parting strip and a flange 100 arranged along each side of said parting strip, and window sashes each having flanges combining to form a groove for receiving one of the first named flanges, one of the flanges of each sash contacting a side of 105 said parting strip. 110
3. In a window construction, a window frame having side and top sections each including outer, intermediate and inner members, said intermediate members being 115 formed with a parting strip, the sides of which are provided with grooves, and opposed faces of said outer and inner members being also provided with grooves, and window sashes including flanges engageable 120 with the sides of said parting strip and said opposed faces and cooperating with said grooves to form air chambers. 125
4. In a window construction, a window frame having side and top sections each including outer, intermediate and inner members, said intermediate members being 130 formed with a parting strip, the sides of which are provided with grooves, and opposed faces of said outer and inner members

- being also provided with grooves, and window sashes including flanges engageable with the sides of said parting strip and said opposed faces and cooperating with said 5 grooves to form air chambers, said flanges also cooperating with said sections to form other air chambers.
5. In a window construction, a window frame having side and top sections each 10 including outer, intermediate and inner members, said intermediate members being formed with a parting strip and a flange arranged on each side of said parting strip to provide a groove, and sashes mounted in 15 said frame and including stiles, each stile having a flange engageable in said groove, and another flanges cooperating with the last named flange to provide another groove for receiving the adjacent flange of one of 20 the intermediate members.
6. In a window construction, a window frame including a sill section having an upwardly projecting portion and a flange adjacent one side of said portion to form a 25 groove, and a sash mounted in said frame and having a rail including a flange disposed on each side of said upwardly projecting portion, one of said flanges being
- engageable with the adjacent side of said portion when the sash is in closing position, 30 and the other flange being provided with a third flange which forms with said flange a groove for receiving the flange on said sill section and which engages in the groove formed in said sill section. 35
7. In a window construction, a window frame including a sill section having an upwardly projecting portion and a flange adjacent one side of said portion to form a 40 groove, and a sash mounted in said frame and having a rail including a flange disposed on each side of said upwardly projecting portion, one of said flanges being engageable with the adjacent side of said portion when the sash is in closing position, 45 and the other flange being provided with a third flange which forms with said flange a groove for receiving the flange on said sill section and which engages in the groove formed in said sill section, the first two 50 named flanges of said rail combining with said sill section to form an air chamber.
